UNITED STATES PATENT OFFICE.

MICHAEL BERARDINI, OF NEW YORK, N. Y.

CODE MESSAGE.

No. 889,094.

Specification of Letters Patent. Patented May 26, 1908.

Application filed December 26, 1907. Serial No. 408,120.

To all whom it may concern:

Be it known that I, MICHAEL BERARDINI, a citizen of the United States, residing at Fort Wadsworth, Staten Island, in the borough and county of Richmond, city and State of New York, have invented certain new and useful Improvements in Code Messages, of which the following is a specification.

10 My invention relates to code messages, particularly such as are used for telegraphic transmission, and has for its object to secure at the same time secrecy of contents, conciseness in form (and hence, low telegraph or cable charges), and in the preferred form of my invention, exceptional safeguards against mistakes.

I have devised my improvements with especial reference to the conditions prevailing in my banking business, where the same customers will send money more or less regularly to one or more persons abroad.

In the accompanying drawings, which illustrate the practical carrying out of my invention, Figure 1 shows a portion of a record and code book used in writing and deciphering messages according to my invention, and Figs. 2 to 8 show various examples of such messages.

30 The book (Fig. 1) as preferred by me, has its pages ruled to form four columns: A, B, C, D, the first of which contains (preferably consecutive) numerals, each of them thus standing at the left hand end of a row. The 35 second column contains the names of remitting customers and may be headed "Remitter"; the third column contains the names of payees, and the fourth, the payee's address. This last column might be omitted 40 in some cases, yet I find it to be an advantage, especially in cases (as they do occur) in which different payees may bear the same name.

The incorporation of the record number 45 1427 in a telegram, for instance, would thus mean that Enrico Corso orders a certain amount to be paid to Silvio Soli of 19, Via Nuova, Rome. The amount is indicated by an additional figure which has a different 50 meaning according to the position it occupies. The numbers in the column A may run up to 9999 (or even to 10000) with the particular system here described. In this particular system, I limit to five figures the code

number which identifies an individual draft 55 or remittance. In my business, the large majority of drafts are for amounts of even hundreds (from 100 to 900) or even tens (from 10 to 90), and I have devised the following simple arrangement: A figure placed 60 in front (at the left) of the record number will indicate a remittance of so many hundred lire, or whatever may be the monetary unit in the payee's country. For instance, 31427 would mean that Enrico Corso orders 65 three hundred lire to be paid to Silvio Soli of 19 Via Nuova, Rome. Of course, my correspondent in Italy to whom such a telegram is sent, would have a duplicate of my record book and full instructions for deciphering such telegrams.

When the code number formed by placing the hundreds figure to the left of the record number, contains less than five figures, I complete it by the addition of one or more 75 naughts, as for instance 04789, which would mean that 400 lire are sent from the remitter to the payee, whose names (together with the payee's address) will be found upon looking up number 789 in the record book. Similarly, 00526 would mean that 500 lire are to pass between the persons indicated by number 26 in the record book. If only one order were to be telegraphed, the inclusion of the zero might not be necessary (although even 85 then it is preferable, to guard against error); but in actual practice, a telegram always refers to a number of orders, and the first thing the recipient (my correspondent) has to do, is to divide the figures into groups of 90 five. If he, therefore, receives a cablegram containing the following:

00025005460710731186,

he will immediately transcribe or divide it 95 to mean:

00025 00546 07107 31186,

thus indicating four remittances of 200, 500, 700 and 300 lire, the sender and payee of 100 which are fully indicated by the record numbers, 5, 46, 107, and 1186, respectively.

As a check for accuracy in transmission, I prefer to add, after the figures, an indication of the number of drafts or orders, together 105 with the total amount in lire and also the sum of the record numbers, or "Special" numbers, as I refer to them in Italian.

Omitting my correspondent's cable address and my signature, the complete cablegram might be as follows, (see Fig. 2):

5 00025005460710731186 ordini 4
lire 1700 speciali 1344.

This would mean that the telegram refers to four orders or drafts totaling 1700 lire and containing "special" or record numbers 10 whose sum is 1344. Errors in transmission would thus be detected easily.

The reason I prefer to limit the code number to five figures is that this is the number of figures which the cable companies now 15 charge as one word.

When I wish to telegraph remittances of 10, 20, 30, ... 90, lire, I indicate this to my 20 correspondent by using some other word, for instance "Diversi" instead of "Speciali," 25 and preferably in this case the figure indicating the amount of the remittance is placed differently, for instance at the right of the record number, instead of at the left thereof. Thus (see Fig. 3)

25 013272584179643 ordini 3
lire, 110 diversi 10680,

would mean that there are three orders (indicated by the code numbers 01327, 25841, 30 and 79643, respectively), that the last figure of each code number indicates tens of lire, that the total amount of the three orders (70+10+30 lire) is 110 lire, and that the 35 sum of the three record numbers (132+2584 +7964) is 10680.

The different placing of the value figure or money figure is only an additional safeguard against errors; for if the sender of the telegram by mistake used the word "Speciali" 40 when the meaning would require the word "Diversi," the test of the addition would reveal the mistake at once. Of course, telegrams of the two forms shown in Figs. 2 and 3 respectively could be combined into one.

45 It will be obvious that the word "Diversi" might be placed ahead of the orders to which it refers, and the code number might follow the figure indicating the value of the order. Thus Diversi 07132 might be used to intimate 50 that 70 lire is to pass between the two persons indicated by the record number 132. The word "Speciali" might in this case be used in the same way as explained in connection with hundreds, to precede the total 55 of the record numbers. Fig. 4 shows the same message as Fig. 3, but expressed in the manner just suggested.

60 By the use of various words, the meaning of the value figure might be varied. Thus 07132 (without any word preceding) would mean 700 lire on account No. 132 just as 00025 in Figs. 2 and 5 means 200 lire on account No. 5; Diversi 07132 would mean 70 lire on account No. 132 as in Figs. 4 and 5; 65 Mille 07132 would mean 7000 lire on account

No. 132, just as Mille 02658 in Fig. 5 means two thousand lire on account No. 658. All this, together with the other features which I am going to describe, is illustrated by Fig. 5.

70 It has been explained that the record number consists of no more than four figures; this apparently would enable me to have only 10,000 accounts or numbers in the record book (four naughts would stand for 75 10,000). By the use of code words I could, however, increase the available number to 20,000, 30,000 or more. For instance, if the word Dieci precedes a section of the telegram, this would mean that 10,000 is to be 80 added to the record number, and that the first figure means hundreds of lire; thus Dieci 07132 would mean that 700 lire are to pass between the persons indicated by the record number 10132; Diecidi 49763 might 85 mean that 40 lire are to pass between the persons indicated by the record number 19763; Diecimil 35848 might indicate that 3000 lire are to be remitted from a certain person to a certain other person both indicated by the record number 15948. These 90 code words may be selected quite arbitrarily.

95 There are various other ways in which the principle of my invention may be carried out. For instance instead of using figures (numerals) as elements for the code part of the message, I may employ letters as shown in Fig. 6, or a combination of letters and figures as shown in Fig. 7. Thus, instead of designating the accounts or rows of the record 100 book by consecutive numbers, I might designate them by letters or combinations of letters, such as *a*, *b*, *aa*, *ac*, *bf*, *cdf*, *ehad*, arranged alphabetically so as to be found readily. Even in this case, I prefer to use 105 record numbers in addition, so that the test or check of the total of record numbers may be available. Instead of the figures indicating values, I may employ, say the last nine or ten letters of the alphabet. Each 110 code unit (say of five elements, as before) would then be of the following character, *xdgfd*, the letter *x* indicating the value, for instance 20000 lire (*x* standing for 2), and *bdgfd* being the record mark corresponding to 115 the record number, and identifying both parties to the transaction. If figures are used to indicate value, the same order will be expressed by *2bdgfd*. Words like "Diversi" or "Mille" would be unnecessary in this case, 120 the position of the value figure or letter being a sufficient indication. Thus *f2bdg* (or *fxbdg*) would mean 2000 lire between the parties indicated by the record mark *bdgfd*; *gfdxbd* (or *gfd2bd*) would mean 200 lire between the same parties, and so on. Gaps would be filled by the letter *z*. Thus *dzzxc* 125 would mean the sending of 20 lire between the persons indicated by the record mark *cd*. Still another possibility is the use of various 130

code words to indicate the value of each order, and of other code words to form a record mark, the two together forming a code unit. This is illustrated by Fig. 8. Thus 5 "Romadidi" might by its first half "Roma" (forming the record mark) indicate for instance, the parties entered in the record book under No. 2376, while the second half "didi" (forming the value mark) might mean 4040 lire. In the same way, the first half "Oro" 10 of the code unit "Orofino" may be a record mark indicating say the record number 385, and the second half "fino" might mean 150 lire. Again the third code unit shown in 15 Fig. 8, the word "Lavasoli" might by its first part "Lava" indicate the record number 1968 and by its second half "soli" the value of 275 lire. The message as shown also contains statements similar to those of Figs. 2, 20 3 and 4, that is, the number of orders (Ordini 3), the total amount (Lire 4465) and the total of the record numbers (Speciali 4729). These statements or indications of totals 25 may of course be used in connection with any form of my message, including those shown in Figs. 5, 6 and 7. It will be understood that Fig. 5 is theoretical, illustrating features, all of which in practice will seldom if ever occur in the same message.

30 In any event, the code part of the message consists of a number of code units each comprising two parts or portions, to wit: a record mark and a value mark. In the preferred form of my invention, the code part 35 of the message contains elements (letters and figures) whose number is an entire multiple of the number of elements constituting a code unit (five elements in the examples described with reference to Figs. 2 to 8.) In 40 these seven figures, the value mark consists of a single element indicating the value or amount of the order, while the other portion of each code unit (comprising not more than four elements) is the record mark indicating, when looked up in the record book, the remitter's and payee's names and the payee's address. Each message preferably also includes the three checks or safeguards above set forth, viz: 1) a statement of the number 45 of orders; 2) the total amount of the orders; and 3) the sum of the record numbers. Further, by the omission or use of means or symbols, such as "Diversi," I indicate whether the element indicating the value is to be 50 read as hundreds or tens, etc. Thus, in Fig. 2 the code part of the message consists of the two lines beginning with 00025 and ending with 1344. On the first of these lines there are four code units (the last of them 55 being 31186) each composed of five figures or elements, so that the total number of elements (20) is a multiple of the number of individual elements (5) constituting a code unit. Each of these code units consists of 60 two portions; one of them, designated (for

the last unit) by the reference character X, indicates the value or amount of the order; the other, to which the reference letter Y has been applied, is the record number or record mark identifying the parties to the 70 transaction. The word and figure "Ordini 4" constitute a statement of the number of orders contained in the message; the word and figures "Lire 1700" (indicated by the reference letter T) give the total amount of 75 the orders; the number 1344 (designated by the reference letter R) is the sum of the record numbers; and the word "Speciali" (referred to by the letter S) constitutes means indicating the value of the elements (such 80 as X) representing the amounts of the orders, since this word indicates to the recipient of the message that the figure 3 of the last code unit means 300 lire, and so on.

I claim as my invention:

1. A code message comprising a series of elements, the number of which is a multiple of the number of individual elements constituting a code unit, each code unit consisting of two portions, one of which indicates 90 the value or amount of the order, while the other is a record mark identifying the parties to the transaction in connection with a record number, the message also including a statement of the number of orders it contains, the 95 total amount of such orders, the sum of the record numbers, and means indicating the value of the elements representing the amounts of the orders.

2. A code message comprising a series of elements, the number of which is a multiple of the number of elements constituting a code unit, each code unit consisting of two portions, one of which indicates the value or amount of the order, while the other is a 100 record mark identifying the parties to the transaction in connection with a record number, the message also including a statement of the number of orders it contains, the total amount of the orders, and the sum of the 110 record numbers.

3. A code message comprising a series of elements, the number of which is a multiple of the number of elements constituting a code unit, each code unit consisting of two 115 portions, one of which indicates the value or amount of the order, while the other is a record mark, identifying the parties to the transaction in connection with a record number, the message also including a statement of the total amount of the orders and the sum of the record numbers.

4. A code message comprising a series of elements the number of which is a multiple of the number of elements constituting a 125 code unit, each code unit consisting of two portions, one of which indicates the value or amount of the order, while the other is a record mark identifying the parties to the transaction, the message also including 130

means indicating the value of the elements representing the amounts of the orders.

5. A code message comprising a series of elements, the number of which is a multiple of the number of elements constituting a code unit, each code unit consisting of two portions, one of which indicates the value or amount of the order, while the other is a record mark identifying the parties to the 10 transaction.

6. A code message consisting of code units each of which comprises two portions, one of said portions being a record mark identifying both parties to the transaction, while the 15 other is a value mark determining the amount to be paid.

7. A record book for use in drafting and

deciphering code messages, having a column containing record marks, another column containing remitters' names, a third column 20 with payee's names, and a fourth with payees' addresses.

8. A record book for use in drafting and deciphering code messages, having a column containing record marks, another column 25 containing remitters' names, and a third column with payees' names.

In witness whereof I have hereunto set my hand in the presence of two subscribing witnesses, this 17th day of December, 1907.

MICHAEL BERARDINI.
